UNITED STATES PATENT OFFICE.

FRANK HOWARD REID, OF MEMPHIS, TENNESSEE, ASSIGNOR TO SUCCESS
BRICK MACHINERY COMPANY, OF MEMPHIS, TENNESSEE, A CORPORA-
TION.

BRICK-CAR.

No. 818,851.

Specification of Letters Patent.

Patented April 24, 1906.

Application filed May 12, 1905. Serial No. 260,154.

To all whom it may concern:

Be it known that I, FRANK HOWARD REID, a citizen of the United States, residing at Memphis, in the county of Shelby and State 5 of Tennessee, have invented certain new and useful Improvements in Brick-Cars, of which the following is a specification.

My invention relates to a car provided with brick-elevating mechanism.

One of the objects of the invention is to provide, in combination with a suitable brick-supporting deck, a step-movement lifting mechanism of the hoisting-jack type.

Another object of my invention is to provide actuating mechanism for the jack so constructed and organized with reference to the jack and car as to be operated from either end of the car.

Another object of my invention is to provide mechanism for reversing the feed of the jack having actuating devices, also adapted to be operated from either end of the car.

Another object of my invention is to provide a suitable form of lever transmission mechanism between the jack mechanism and the movable brick-support for imparting the raising and lowering movements to said movable support.

Another object of the invention is to so organize these various mechanisms as to dispose the lifting strain directly over the bearings of the wheels upon the rails.

Such disposition of the parts avoids strains between the bearings, which have a constant 35 tendency to throw the car and its lifting mechanism out of true, which greatly shortens the life of the entire machine.

Another object of the invention is to provide a vertically-movable deck or brick-support having certain improved guiding features and connections with the lifting mechanism, which will be later more fully described.

The features of the invention are more fully set forth in the description of the accompanying drawings, forming a part of this 45 specification, in which—

Figure 1 is a top plan view. Fig. 2 is a central vertical section through Fig. 1. Fig. 3 is a detailed side elevation, partly in section, 50 with parts removed, showing the actuating devices for reversing the jack-feed. Fig. 4 is a view similar to Fig. 3, showing the opposite side of the car with the mechanism for actu-

ating the jack. Fig. 5 is a section on line $z-z$, Fig. 1, showing the position of the jack mechanism relative to the center of the car and the stirrup and with the movable frame removed. 55

The truck consists of the usual frame 1, wheels 2, and axles 3. The axles are reinforced by the bolsters 4, forming supports for the fulcrums of the various lever mechanisms, whereby the lifting and operating strains are thrown directly over the wheel-centers. Across the intermediate portion of the truck is thrown a platform 5, from which is suspended a housing 6, containing a jack mechanism, this housing being depended below the truck. Projecting from the lower end of the housing is the ratchet-bar 7, to which is imparted a vertical step-feed movement by the jack mechanism within the housing. It is not essential to illustrate or describe the housed details of the jack mechanism, as numerous well-known forms would answer. Projecting from one side of the housing is the 75 actuating crank-shaft 8, (see Figs. 4 and 5,) having the crank-arm 9. This crank-arm, it will be observed, is intermediately secured upon the end of shaft 8, and to the opposite end of arm 9 are respectively pivoted the 80 links 10, which are projected in opposite directions to the opposite ends of the truck. From the bolsters 4 are forwardly projected the struts 11, to the front ends of which are fulcrumed the hand-levers 12, the inner ends of 85 which are in turn respectively fulcrumed to the outer ends of the links 10. Upon the opposite side of the housing from the projecting end of shaft 8 is an eccentric 13, (see Fig. 3,) having a pin 14. 15 is a crank-arm fixed to 90 said pin, and 16 represents arms or actuating-rods secured to each other and to said crank-arm 15 and projected to the opposite ends of the truck, as shown in Fig. 3. (See also Fig. 5.) The present invention is not concerned with 95 the details of this reversing mechanism, which may be of any approved pattern. It is obvious that from either end of the car the ratchet-bar 7 can be fed vertically in either direction. This is of practical convenience, as 100 it saves the operator the necessity of unnecessarily walking around the car.

I will now describe the lifting mechanism actuated by the ratchet-bar.

17 represents two levers tied together by a 105 rod 18. 19 20 represent similar levers and

tie-rods. The pairs of levers 17 19 are fulcrumed between their ends, respectively, upon the opposite bolsters 4, the levers being pivoted so that at their outer ends they extend outside of and above the truck. Their inner or meeting ends extend below the truck substantially under the platform 5, and these inner ends have a slotted pivotal connection with the upper ends of a substantially U-shaped frame 21. (See Figs. 2 and 5.) The lower end of the ratchet-bar 7 engages upon the cross-piece of the U-shaped frame 21. The upper ends of said levers 17 19 are provided with the antifriction-rollers 22.

23 represents rails trussed together to form a deck or support. The rollers 22 have their inner flanges engaging the inner surfaces of the rails 23. By this means the deck or support seats upon the upper ends of the levers 17 19 and has a substantially antifriction sliding engagement therewith. To prevent the support from longitudinal movement relative to the truck, the support has a guide member having depending arms 24 (see Fig. 2,) which engage the opposite sides of the platform 5.

It is obvious that as the ratchet-bar is actuated to move it downward its lower end straining downward upon the stirrup 21 will move it downward, depressing the inner ends of levers 17 19 divergently, the upper ends of said levers being raised convergently and so sliding under and lifting the support 23. When the feed mechanism is reversed and the ratchet-bar is retracted into the housing, the support will be lowered. The inner ends of the said levers 17 19 have a slotted engagement with the stirrup 21 to permit of their longitudinal movement. By this mechanism the support may be lifted in a true horizontal plane in step movements by an easy and convenient manipulation.

Having described my invention, I claim—

1. In combination with a car truck and wheels, a lifting-jack supported by the truck, a vertically-movable brick-support seated upon the truck, connections between the jack and said support, for imparting a vertical feed to the support, a crank shaft and arm for actuating the jack, lever mechanism pivotally connected to said arm and fulcrumed at opposite ends of the car-truck, means for reversing the direction of movement of the jack, and actuating devices for the said reversing mechanism projected to the opposite ends of the truck, substantially as described.

2. In combination with a car truck and wheels, a platform straddling the truck, a jack mechanism secured to the under face of the said platform, said jack having a ratchet-bar movable vertically under the platform, a lever mechanism fulcrumed upon the truck, having a stirrup engaging under the end of said ratchet-bar, the upper ends of said lever

mechanism projecting above the truck, and forming a seat for the movable support, means permitting a sliding engagement of the said supporting-lever ends with the said brick-support, means for feeding said ratchet-bar in either direction, and an actuating-lever, substantially as described.

3. In combination with a car truck and wheels, a platform straddling the truck, a movable brick-support, a jack mechanism secured to the under face of the platform and comprising a ratchet-bar movable vertically under the platform, a substantially U-shaped stirrup engaging under the end of the ratchet-bar, lever mechanism pivoted to the opposite arms of said stirrup, said lever mechanism being extended to the opposite ends of the truck and fulcrumed thereto substantially over the wheel-axles, the upper ends of said lever mechanism projecting above the truck and forming a seat, adapted to slidably engage and support the said movable brick-support, means for feeding the said ratchet-bar in opposite directions, and an actuating-lever, substantially as described.

4. In combination with a car truck and wheels, a platform straddling the truck, the said truck being provided with bolsters in line with the wheel-axles, a jack mechanism secured to the under face of the platform and comprising a ratchet-bar movable vertically under the platform, a substantially U-shaped stirrup engaging under the end of the said ratchet-bar, lever mechanism, the inner ends of which are pivoted to the upper ends of the said stirrup, said lever mechanism extending to opposite ends of said truck and fulcrumed upon said bolsters, the upper ends of said lever mechanism being extended above the opposite ends of the truck and forming a seat, adapted to slidably engage and support the brick-support, means for feeding said ratchet-bar, and an actuating lever mechanism therefor, substantially as described.

5. In combination with the car truck and wheels, a vertically-movable support, a platform, straddling the truck between the wheels, a vertically-feeding mechanism secured under the platform, a lever mechanism fulcrumed at the opposite ends of the truck, the inner ends of which engage the vertical feeding mechanism, the upper ends of said lever mechanism forming a sliding seat for the said support above the truck, substantially as described.

6. In combination with a car truck and wheels, a platform straddling the truck, a movable brick-support, a jack mechanism secured to the under face of the platform and comprising a ratchet-bar movable vertically under the platform, a substantially U-shaped stirrup engaging under the end of the ratchet-bar, lever mechanism pivoted to the opposite arms of said stirrup, said lever mechanism being extended to the opposite ends of the

truck and fulcrumed thereto substantially over the wheel-axles, the upper ends of said lever mechanism projecting above the truck and forming a seat adapted to slidably engage and support the said movable brick-support, and an actuating-lever, substantially as described.

7. A brick-car having a truck, a brick-supporting deck vertically movable thereon, a platform supported across the truck, a jack mechanism secured to the platform, connections between the deck and the vertically-movable element of the jack, and reversing mechanism, whereby the jack may be fed in opposite directions, substantially as described.

8. In combination with a car truck and wheels, a lifting-jack supported by the truck, a vertically-movable brick-support seated upon the truck, connections between the jack and said support, a crank-shaft and arm for actuating the jack, a lever having connection with said arm for actuating said jack, and jack-reversing mechanism whereby said lever may be operated to raise or lower the brick-support, substantially as described.

In testimony whereof I have hereunto set my hand.

FRANK HOWARD REID.
